UNITED STATES PATENT OFFICE.

CLARENCE F. BAER, OF SHICKSHINNY, PENNSYLVANIA.

MUSIC-LEAF TURNER.

Application filed September 11, 1924. Serial No. 737,120.

This invention relates to music leaf turners especially adapted to be used upon piano and organ cases, and it consists in the novel feature hereinafter described and claimed.

An object of the invention is to provide a music leaf turning mechanism of simple structure adapted to be operated by a foot pedal and which includes means for engaging and turning the leaves successively, and when the leaves are supported upon the disc panel of the casing.

With this object in view, the music leaf turner comprises a frame adapted to be applied to the disc of the instrument casing. A shaft is journalled upon the frame, and a series of arms is loosely mounted upon the shaft. Each of the said arms is provided with crimps adapted to engage the music leaves. A bracket arm is fixed to the shaft and carries a head provided with a pawl adapted to engage lugs mounted upon the first mentioned arms, whereby the loose arms are temporarily fixed with relation to the shaft, and will turn with the shaft when the shaft is turned. A release arm is mounted upon the frame, and is located in the path of movement of a pin which is carried by the pawl, and when the said pin rides upon the shunt arm, the pawl is moved out of engagement with the lug which is fixed to the arm, and which is loose upon the shaft. The device also includes a foot pedal, there being means operatively connected with the said foot pedal, and the shaft whereby the said shaft is turned when the pedal is depressed. Means are provided for returning the shaft when the pedal is released.

In the accompanying drawings:

Figure 1 is a front elevation of a piano casing, with the music leaf turner applied thereto.

Figure 2 is an enlarged fragmentary horizontal sectional view through the disc panel of the instrument casing, and showing the music leaf turner in top plan.

Figure 3 is a fragmentary vertical sectional view of the lower portion of the instrument casing, showing the pedal mechanism for operating the music leaf turner in side elevation.

Figure 4 is a perspective view of the outer end portion of the bracket arm of the music leaf turner, showing the head mounted thereon, and the pawl which is pivoted upon the head.

In the accompanying drawing, the piano or organ casing is indicated at 1, and the said casing is provided with the usual pivoted disc panel 2. A frame 3 is mounted upon the outer surface of the disc panel 2, and is provided with a ledge 4, upon which the lower edges of the sheets of music (not shown) may rest. A release arm 5 is mounted upon the upper portion of the frame 3, and the said arm is provided with a forwardly and downwardly inclined end portion having a lug 7 mounted thereon and spaced from the end edge thereof. A shaft 8 is journalled upon the frame 3, and a bracket arm 9 is fixed to the said shaft. A head plate 10 is fixed to the outer free end of the bracket arm 9 and is provided with a ledge portion 11, a pawl 12 is pivoted upon the head plate 10, and the lower edge thereof is normally held in contact with the upper surface of the ledge 11, by a spring 13, which is connected at one end with an angularly disposed end portion 14, of the pawl, and connected at its other end with an upstanding arm 15 provided at the upper edge of the head plate 10. The pawl 12 is provided with a chamfered end 16, and said pawl is provided at its lower edge portion with a notch or recess 17. The free end of the pawl 12 is pointed, and the free end portion thereof is provided with an outstanding end 18. A series of arms 19 is loosely mounted upon the shaft 8, one upon the other, and each arm is provided with a pair of clips 20, adapted to engage the upper edge portion of the sheet of music. Each arm 19 is provided at the point between its ends with a lug 21 and the lugs 21 have angularly disposed end portions as best shown in Figure 4 of the drawing. The upper end portions of the lugs 21 are adapted to be received respectively in the recess 17 of the pawls 12, as the arm 9 and head plate 10 are turned or moved, as hereinafter explained.

A gear wheel 22 is fixed to the upper portion of the shaft 8, and meshes with the teeth of the gear segment 23, which is fixed to the upper end portion of the shaft 24, the said shaft 24 being journalled at the back of the disc panel 2, and the segment 23 passing through the said panel as best shown in Figure 2 of the drawings. The shaft 24 is provided, at its lower end with a crank 25. A shaft 26 is journalled in the casing 1, and is provided at its upper end

with a crank 27. A rod 28 is pivoted at one end to the free end of the crank 25 and pivoted at its other end to the free end of the crank 27. A gear wheel 29 is 5 mounted upon the intermediate portion of the shaft 26. A pedal 30 is riveted upon a bracket 31, which is located within the casing 1, and one end of the said pedal 30 passes through the front of the casing, 10 as best shown in Figure 3 of the drawing. A spring 32 is connected at one end with the casing, and at its other end with the intermediate portion of the pedal 30. A spring 33 is located in the casing 1, below 15 the pedal 30, and serves as means for cushioning the downward movement of the pedal 30, when the same is depressed by using the foot. The pedal 31 is provided at its inner end with an upstanding arm 34 carrying a gear segment 35, the teeth of 20 which mesh with the gear wheel 29 hereinbefore described.

From the above description, it will be 25 apparent that when the pedal 30 is depressed, the gear segment 35 is moved transversely of the shaft 26, and inasmuch as the teeth of the segment 35 are in mesh with the teeth of the gear wheel 29, the shaft 26 is turned or rotated. As the said shaft 26 is 30 turned, the crank arm 27 moves the bar or rod 28 longitudinally, whereby the shaft 24 is turned. In that the gear segment 23, which is mounted upon the shaft 24 meshes with the gear wheel 22 mounted upon the 35 shaft 8, the shaft 8 is turned. When the shaft 8 is turned, the arm 9 is swung in one direction. As soon as pressure is released from the pedal 30, the tension of the spring 32 comes into play, and the pedal 30 is 40 moved in an upward direction, and the movement of the connecting parts between the pedal 30 and the arm 9 are reversed, so that the arm 9 is swung in an opposite direction or returned to its normal position. 45 Assuming that the position as shown in Figure 2 of the drawing is the normal position for the arm 9, and that the lug 21 of the outer arm 19 is in the recess 17 of

the pawl 12, it will be seen that, when the 50 pedal 30 is depressed, the arm 19 is swung with the arm 9, so that the pawl 12 is moved toward the release arm 5. As the pawl 12 approaches the release arm, the pin 18 rides up over the surface of the end portion 6 of the arm, and the side edges of the recess 55 17 are lifted above the upper angularly disposed extremity of the lug 20. Thus, the arm 19 is turned, and at the end of its turning movement, the lug 21 carried thereby is released from the pawl 12. When 60 the pin 18 strikes the lug 20, the arm 9 comes to a state of rest. At this time the pressure is released from the pedal, and the head plate 10 which is carried at the outer 65 end of the arm 9, is swung away from the release arm 5, by spring 32 actuating pedal 30 as heretofore indicated and the chamfered ends 16 of the pawl 12 engage the angularly disposed extremity of the lug 21 upon the next arm 19 so that said pawl is 70 lifted to allow said lug to engage in the recess 17.

What is claimed is:

A music leaf turner including a frame, a release arm mounted on the frame and provided with an upstanding lug, a shaft journaled upon the frame, means for turning and returning the shaft, a bracket arm fixed to the shaft, a head plate carried by the bracket arm and provided with ledge plate, 75 a pawl pivoted upon the head plate and provided with a notched edge, spring means for holding the notched edge of the pawl in contact with the ledge plate, a pin extending from the free end of the pawl, the lug upon the release arm being disposed in the path of movement of the pawl, as the bracket arm moves toward the release arm, a music leaf supporting arm rotatable independently of the shaft, and a lug on the 80 music leaf carrying arm having its upper portion in the path of movement of the pawl so as to be engaged thereby.

In testimony whereof I affix my signature.

CLARENCE F. BAER.
